CLAIM

The ornamental design for a medical atomizer for nasal cavity, as shown and described.

DESCRIPTION

FIG. 1 is a front, top, and right side perspective view of a medical atomizer for nasal cavity showing my new design; FIG. 2 is a front view thereof;

FIG. 3 is a rear view thereof;

FIG. 4 is a top plan view thereof;

FIG. 5 is a bottom plan view thereof;

FIG. 6 is a right side view thereof;

FIG. 7 is a left side view thereof; and,

FIG. 8 is a cross-sectional elevation view of the medical atomizer for nasal cavity, taken in the direction of 8-8 of FIG. 6.

The broken lines illustrate portions of the medical atomizer for nasal cavity that form no part of the claimed design.

1 Claim, 7 Drawing Sheets
